COMBINED BACKGUARD AND CONTROL PANEL FOR A RANGE

Melvin H. Boldt, Glenview, Ill., assignor to AVCO
Manufacturing Corporation, Cincinnati, Ohio, a corpora-
tion of Delaware

Application December 28, 1955, Serial No. 39,508

Term of patent 3½ years

(Cl. D81—25)

Fig. 2 +₄

Fig. 3

Fig. 1

Fig 4

Figure 1 is a perspective view of a combined backguard and control panel for a range showing my new design, the dotted line showing of the range being for illustrative purposes only;

Figure 2 is an enlarged front elevational view of the panel;

Figure 3 is a side elevational view thereof; and

Figure 4 is an enlarged cross-sectional view taken on line 4—4 of Figure 2.

I claim:

The ornamental design for a combined backguard and control panel for a range, as shown and described.
